UNITED STATES PATENT OFFICE.

JOHN E. ADAMS, OF RHINELANDER, WISCONSIN.

PORTABLE BUNGALOW.

Application filed May 6, 1922. Serial No. 558,919.

To all whom it may concern:

Be it known that I, JOHN E. ADAMS, a citizen of the United States, residing at Rhinelander, in the county of Oneida and 5 State of Wisconsin, have invented certain new and useful Improvements in Portable Bungalows, of which the following is a specification.

This invention relates to a portable 10 bungalow and one object of the invention is to provide a bungalow having an improved wall construction consisting of a plurality of sections which are securely but removably connected so that the bungalow may 15 be formed a desired size and easily set up or taken down and when set up the sections connected by improved joint structures which will provide for a close and substantially air-tight fit between the sections.

Another object of the invention is to so 20 construct the sections that they will be provided with dead air chambers between inner and outer facing panels, the outer panel of each section being formed of split logs 25 secured to a section frame and stripped to prevent air passing between the logs and the inner panel being also formed of split logs or plaster board backed with building paper and providing sections which will be air-tight and serve very effectively to exclude 30 cold.

Another object of the invention is to so construct the sections that when set up and connected the walls will each present the 35 appearance of being formed of logs placed vertically in side to side contact and the bungalow when finished have the appearance of a log cabin.

Another object of the invention is to so 40 construct the sections that if desired the inner panels thereof may be left off and thus provide a bungalow with walls having unfinished inner faces without weakening the wall sections or necessitating change in the 45 construction of the frames or joint structures of the sections.

Another object of the invention is to so 45 construct the sections that they may be very easily and quickly set up or taken apart and 50 when set up and joined provide a substantial structure which will not accidentally come apart.

This improved bungalow is illustrated in the accompanying drawings, wherein:

55 Figure 1 is a perspective view of the assembled bungalow with the roof removed.

Figure 2 is a view showing in perspective the sections forming a forward corner of the bungalow, the sections being separated.

Figure 3 is a perspective view of the assembled forward corner sections looking from the inside of the bungalow.

Figure 4 is a view similar to Fig. 3 showing the sections separated.

Figure 5 is a perspective view showing certain of the wall sections separated and looking at their outer faces.

Figure 6 is a perspective view looking at the inner faces of the separated sections shown in Fig. 5.

Figure 7 is a view showing the sections of Fig. 6 put together.

Figure 8 is a perspective view showing the sections forming a rear corner.

Figure 9 is a perspective view showing the sections of Fig. 8 put together and cap strips about to be put in place.

Figure 10 is a view showing the cap strips in place.

Figure 11 is a transverse section through one of the sections.

Figures 12 and 13 are similar views showing modifications.

This bungalow may be provided with a suitable foundation including supporting 85 posts and a flooring carried thereby which may be formed in sections if so desired and space below the flooring closed by boarding or left open. The invention however does not reside in the flooring or floor supports 90 but resides in the construction of the walls and porch, the walls and porch being formed in sections which are so constructed that they may be readily put together and securely connected by joints at their adjoining ends 95 or sides. These joints are so constructed that when fasteners such as nails or screws are put in place, the sections will be prevented from having movement towards and away from each other and also prevented 100 from having vertical movement.

The rear wall is provided with end sections 1 and between the end sections 1 will be placed one or more sections 2, the number being in accordance with the size of the 105 bungalow it is desired to build. These sections may be provided with windows 3 or may be formed as solid sections, the windows being of a conventional construction and set in place when building the sections.

The side walls are provided with forward and rear sections 4 and 5 which in the form

2
shown are directly connected. It is to be understood that intermediate sections similar to the sections 2 may be provided between the sections 4 and 5 if it is desired to have a deeper building. The rear sections 5 are connected with the end sections 1 of the rear wall and the forward sections 4 are connected with the front wall and end portions of the porch.

10 The front wall is provided with end sections 6 and 7 and one or more intermediate sections 8 and in the form shown the intermediate section is provided with a door frame 9 and the section 6 has been provided 15 with an elongated window frame 10. If desired this could be reversed and the door provided in the section 6 or the section 6 could be made shorter, the door carrying section placed next to it and additional sections 20 with or without windows placed between the sections 8 and 7.

The porch will be provided with upper and lower end sections 11 and 12 and upper and lower front sections 13 and 14. The upper sections 13 are supported by posts 15 placed at the corners and intermediate the length of the porch. By providing additional sections 13 and 14, a porch of the proper length can be provided to accommodate 30 itself to a bungalow having a greater width than the one shown. It will thus be seen that a bungalow of any size and dimensions may be formed by providing the corner sections and the proper number of intermediate sections and that the desired number of doors and windows may also be provided through proper selection of sections.

The sections are provided with upper, lower and intermediate rails or bars 16, 18 40 and 17 and to which are secured split logs 19. These logs extend vertically of the sections and since they have side to side contact and have their uncut faces positioned outwardly, the bungalow will have the appearance of being built of logs when the sections are put together. Upper and lower strips 20 and 21 are secured to the rails 16 and 17 and to the ends of the split logs 19 thus providing the sections with finished upper and 45 lower ends and further providing joints as will be hereinafter brought out. After the split logs are secured, thin strips such as laths 22 are nailed to the inner faces of the logs to cover cracks between them and exclude air. The inner faces of the sections 55 may be left unfaced as shown in the principal figures or may be faced as shown in Fig. 12 or as shown in Fig. 13. In the form shown in Fig. 12, sheets 23 formed of tar paper or the like are nailed against the bars to which the logs 19 are secured and split logs 24 are then nailed to these bars against the tar paper. This will provide dead air 60 spaces in the sections and in addition will give the bungalow the appearance of being

built of solid logs. In the form shown in Fig. 13, the tar paper 23 and split logs 24 are left off and plaster board sheets 25 substituted. This form provides the air spaces in the sections but does away with the solid log 70 appearance and provides a less rustic appearance from inside the bungalow.

In order to connect the end sections of the rear and side walls each of the end sections 1 of the rear wall has been provided with 75 vertically disposed abutment strips 26 at the ends of the rails 16, 17 and 18. The rails at this end of the section 1 terminate short of the end of the section thereby providing pockets 27 to receive the ends of the rails 80 of the adjoining side wall section 5. The upper and lower strips 21 have their ends extended and reduced to provide tongues 28 and 29 which overlap as shown in Fig. 9 so that nails or screws may be passed through 85 them and into the split logs 19 to prevent the sections from moving apart. By having the rails of the sections 5 fitting into the pockets of the sections 1, a tight fitting joint is provided and the strips 26 serve to prevent the 90 sections from having vertical movement.

In order to connect the forward side wall sections 4 with the rear sections 5, each section 4 has the rails cut short at the forward end of the section so that the ends of the 95 rails of the section 5 which extend as shown in Fig. 5 may extend behind the split logs of the section 4 against the ends of the rails thereof which terminate short of the end of the section as shown in Fig. 6. The tongues 100 30 at the ends of the strips 21 of the section 4 extend in overlapping relation to the tongues 31 of the section 5 and when fastener screws are passed through these tongues 30 and 31 and through the extended 105 ends of the rails of the section 5 into the end log of the section 4, the two sections will be securely connected and prevented from having any movement. The ends of the section 2 of the rear wall will be secured to the adjoining ends of the sections 1 and if desired sections may be provided between the sections 4 and 5 and joined to them as described above.

The front wall has its intermediate section 8 secured to the end sections 6 and 7 in the same manner that the sections 4 and 5 are secured to each other. The end sections 6 and 7 of the front wall are joined to the forward side wall sections 4 and upper 110 and lower porch sections 11 and 12 as shown in Figs. 2, 3 and 4 and reference will now be had to these figures. Each section 4 has its rails cut short and is provided at its forward end with abutment strips 32 and 33 and a 115 shorter strip or block 34. The rails 16 and 17 of the end sections 11 and 12 of the porch are extended at their rear ends and these extended rail ends extend behind the end log of the section 4. The rail 18 of the 120

lower section 4 and the strip 21 carried thereby has its extended end reduced to provide a tongue 35 which extends in overlapping relation to the tongue 36 of the lower strip 21 of the section 4 and beneath the rail 18 thereof. The tongue 35 is longer than the tongue 36 so that when the porch section 12 is in place with the rail 18 thereof engaging the rail 19 beneath the strip 33 of the section 4, a space or pocket will be left beyond the end of the tongue 36. When the section 12 is in place, the rail 16 thereof and strip 20 carried thereby extend between the strips 33 and 32 to assist in holding the porch section in place and preventing movement thereof. The rails 16 and 18 of the upper porch section 11 are extended as shown in Fig. 4 and extend above and below the block 34 with the rail 18 and strip 21 fitting tightly between the strip 32 and block 34. The upper strip 20 of this upper porch section 11 is extended and reduced to provide a tongue 37 which extends beneath the tongue 38 of the section 4 and is of greater length than the tongue to provide a seat beyond the end of the tongue 38. The end section of the front wall has its strips 20 and 21 provided with tongue extensions 39 and 40 which fit into the seats or pockets beyond the ends of the tongues 36 and 38 and are secured by screws as shown in Fig. 3. The end log of the front wall section is cut to provide seats 41 and 42 and a tongue 43, the seats 42 receiving the rails of the section 12 and the tongue 43 extending between the rails of the section 11 with the lower rail thereof fitting into the seat 41. The adjoining ends of the front and side walls and porch sections will therefore be very firmly connected and will be prevented from moving vertically, pivotally or towards and away from each other. The sections 13 and 14 have their outer ends connected with the sections 11 and 12 by overlapped tongues at the ends of the upper and lower strips after the manner of connecting the end sections of the rear wall with the rear sections of the side walls and the inner ends of the sections 13 and 14 are held in engagement with each other by overlapped tongues after the manner of connecting the sections 4 with the sections 5. The posts 15 which support the upper porch sections 11 and 13 are put in place at the corners and intermediate the length of the porch and are secured by means of screws or other suitable fasteners.

When this bungalow is to be set up, the foundation and flooring are first set up and the walls and porch then erected upon the flooring. As the sections are put together, the ends are connected as previously brought out and the fastener screws put in place. In addition to the sections forming the wall and porch section, the invention contem-

plates the use of top strips 44 which may be termed binding strips and will be secured to the upper edges of the walls and porch and will be connected by overlapping tongues at their points of meeting. The binding strips for the front and rear walls and upper porch sections 13 will be continuous strips the full length of the bungalow and the binding strips for the side wall will extend from the rear wall along the upper edges of the upper sections 11 at the ends of the porch. Therefore when the binding strips are put in place and screwed to the wall and porch sections additional means will be provided to secure the sections together. After the walls and porch have been set up and suitably anchored to the flooring the roof will be put in place and the bungalow is ready for use. The roof has not been illustrated as it does not form part of the invention and any desired roof may be provided. While the roof, flooring and foundation does not form part of the present invention, it is to be understood that they may be supplied with the walls and porch forming sections and a complete bungalow thus supplied in a knock-down condition.

I claim:

1. A portable building comprising walls 95 having sections having vertically disposed panels, rails extending transversely of the panels and secured thereto, strips extending along the upper and lower ends of the panels and secured to the rails and ends of 100 the panels, the end portions of the strips being extended to provide tongues for extending in overlapping relation when the sections are put together and receiving fasteners.

2. The structure of claim 1, having the sections each having the rails at one side terminating short of the side edge of the end panel whereby the end panel at the said side may extend in overlapping relation to 110 rails of an adjoining section and be secured to the same.

3. The structure of claim 1, having the sections each having the rails at one side terminating short of the side edge of the 115 end panel whereby the end panel at the said side may extend in overlapping relation to rails of an adjoining section and be secured to the same, the end panel at the adjacent side of an adjoining section terminating 120 short of the ends of its rails to provide extended rail ends for abutting the ends of the rails of the first section in back of the end panel thereof.

4. The structure of claim 1 having the 125 tongues at one side of a section extending for a portion of the width of the end panel, whereby the tongues of an adjoining section may fit against the exposed ends of the panel and when fasteners are passed through 130

the overlapped tongues secure the sections against vertical and longitudinal movement.

5. The structure of claim 1 and securing strips extending along the upper ends of the 5 sections and secured to the same after the tongues have been secured in overlapping relation and bracing the sections against longitudinal movement.

6. The structure of claim 1 having the 10 corner sections meeting with the rails of one section having their ends engaging the sides of the rails of the second corner section, and abutment strips extending vertically adjacent the end of the first section 15 for fitting between the rails of the second corner section and bracing the sections against vertical displacement.

7. The structure of claim 1 including a porch having upper and lower front and 20 side sections and supporting pillars positioned between and secured to the upper and lower sections, said porch sections having adjoining ends provided with tongue extensions secured in overlapping relation, 25 the side sections having tongue extensions extending in overlapping relation to strips of the corner sections of the side and front walls, and the corner sections of the front wall being provided with cutouts forming 30 sockets receiving rails of the said porch sections and firmly holding the sections together.

8. In a portable building walls including a front wall and a side wall having meeting 35 end sections, a porch including an end portion having upper and lower sections engag-

ing the said front and side wall sections at the junction thereof, the sections of the walls and porch each having outer vertically disposed panels, rails extending transversely 40 of the sections against the inner faces of the panels and upper and lower strips extended to provide tongues, the rails of the porch sections being extended to fit behind the end panel of the side wall section and the side 45 wall section having vertically disposed abutment strips positioned between the rails of the porch sections to hold the porch sections against vertical movement, the tongues of the porch sections being elongated and the 50 tongues of the front wall section overlapping the tongues of the porch section beyond the ends of the tongues of the side wall section, said front wall section having its end engaged by the abutment strip and panel cut 55 to provide pockets receiving the rails of the porch sections.

9. A portable building section comprising outer panels, bracing elements secured against the inner faces of the panels to hold the same in place, upper and lower end strips extending transversely along the upper and lower ends of the section and having extended ends providing tongues for 60 extending in overlapping relation to tongue 65 extensions of other sections and receiving fasteners, and strips extending along the upper ends of the section and secured to the same after the extended tongues have been 70 secured together.

In testimony whereof I affix my signature.
JOHN E. ADAMS.
